The ornamental design for a shoe sole design, as shown and described.

DESCRIPTION

FIG. 1 is a perspective view of a shoe sole showing my new design;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a rear elevational view thereof.

A top view of the shoe sole design has not been shown because it is not an element of the claimed design.
